WRITING BOARD

Edward J. Gerety, Bronx, N. Y., assignor to The
McBee Company, Athens, Ohio, a corporation
of Ohio

Application June 4, 1935, Serial No. 24,796

3 Claims. (Cl. 282—29)

My invention relates to that class of boards which are described in my copending application, Serial No. 709,731 filed February 5, 1934, now Patent No. 2,011,625, August 20, 1935. As described in that application, automatic means are provided for shifting the spacer which carries the strip of paper or a line guide such as shown in Patent No. 1,372,360 March 22, 1921; this operation being brought about by the movement of a plate, one side of which is hinged to the platen and when it presses down upon the platen it holds the slip of paper which is to be written upon and which is attached to the spacer in place. Upon this release the spacer is automatically shifted one line or more as desired. I have found in practice that if the operator turns away from the board before completing his entry on the slip of paper the plate is automatically elevated and this in turn permits the automatic mechanism to shift the line spacer.

The principal object of my present invention is an improvement on that board by providing means to lock the plate in position so that it will not release the strip of paper and consequently will prevent the operation of the automatic mechanism unless manual released by the operator.

A further object is to provide aligning means on the plate which will have the effect of straightening the strip of paper in the event that it has not been placed in correct position so as to register with the lines on the master sheet on the platen or writing board. It is sometimes found that the vertical columns on the master sheet do not register accurately with the vertical columns on the sheet carried by the line spacer. As a consequence the entries are not always in line. I have found that by providing a plurality of lines on the strip of paper instead of a single line I insure the figures appearing in the proper columns.

A further object of my invention is to improve the method of shifting the pawl which is actuated by the movement of the plate.

My means of accomplishing the foregoing objects may be more readily understood by having reference to the accompanying drawings which are hereunto annexed and are a part of this specification, in which—

Fig. 1 is a plan view of my device with a portion thereof broken away;

Fig. 2 is a fragmentary bottom view of my device showing the relation between the spacing member and the worm which operates it.

Fig. 3 is a detailed view of the gear box partly

broken away to show my improved construction of the pawl actuating mechanism;

Fig. 4 is an enlarged vertical section through a portion of Fig. 1;

Fig. 5 is an enlarged view showing the holding mechanism;

Fig. 6 is a section taken on the line 5—5 in Fig. 3;

Fig. 7 is an enlarged detailed view of the opening mechanism;

Fig. 8 is a section on the line 8—8 in Fig. 7; and

Fig. 9 is a plan view of the improved manner of forming the vertical lines on the strip of paper. Similar reference numerals refer to similar parts throughout the entire description.

As shown in the drawings the platen or writing board 1 may be formed of any suitable material. I prefer the use of a light metal such as aluminum rather than of making it of wood or any of the heavier metals. In order to facilitate the placing of the master sheets on the platen, I provide a peripheral upwardly extending flange 2 which extends along the top of the platen along one side, a plurality of studs 3 are mounted on the platen and are adapted to receive perforations formed in the master sheet thus serving to hold the sheets securely in place. On one side of the writing board is a slot 4 through which extends a pair of pins 5 and 5'. Intermediate the pins 5 and 5' I stamp an arrow to facilitate locating the line which is being written on when it is desired to change a master sheet. These pins are adapted to receive a perforated strip of paper 6. This strip of paper 6 represents an entry slip and is provided with a plurality of horizontal and vertical spacers when in position on the board 1 which extends over one or more master sheets 7 and carbons 8. It will be apparent to persons skilled in the art that a multiplicity of entry slips may be used in manifold relation either with the wax carbon spots on the back or carbon paper intermediate or the top sheet of the pile of sheets on the platen. One may be the master sheet and the under surface of the entry slip 6 may be coated with carbon. The pins 5 are carried by a spacer 9 which is preferably formed of a flat plate, one edge of which slides on support 10. At the other side it is formed into a sleeve 11 adapted to encircle a worm 12 which is journaled in the opposite sides of the board. One of the pins 5 is fixedly mounted on the flat plate 9, the other pin 5' is mounted upon a plate 13 which is pivotally secured to the plate 9 by a pin or pivot 14 and is provided with a finger 15 which is

adapted to extend into the groove of the worm 12. The finger 15 is normally pressed into the groove of the worm 12 by a spring 16.

A portion of the plate adjacent this pin is cut 5 away as clearly seen in Fig. 7, thus permitting its movement in order to disengage the finger 15 from the worm 12 when it is desired to quickly shift the position of the spacer from one end of the worm 12 to the other.

10 Rigidly keyed to the upper end of the shaft of the worm 12 is a pinion 17, the teeth of which are in mesh with a gear 18 which is fixedly secured to a shaft 19. Preferably mounted upon the hub of the gear 18 is a ratchet 20, although 15 if desired it may be secured direct to the shaft 19.

A disk 21 is loosely mounted on shaft 19. On one side of this disk 21 is mounted a spring pressed pawl 22 which swings on a pin 23 extending downwardly from one side of the disk 21.

20 This pawl is arranged to engage the teeth of the ratchet 20 when it moves in a counter clockwise direction. The opposite side of the disk 21 is recessed and has a spring 24 mounted therein, one end of the spring being attached to the disk adjacent 25 its hub, the other extending outwardly and being attached to a pin 25 mounted in one wall of the gear box 26 which is secured to the platen 1 adjacent the upper end of the worm 12.

In the inner face of the gear box 26 I form an 30 arcuate slot 27 through which projects a pin 28 which extends laterally from the disk 21. This brings the pin in position to be engaged by the end of a plate 29, the sides of which are hinged to the platen 1 at 30. This plate is sufficiently 35 wide so that it will extend over the entry slip 6.

On the bottom side of the plate 29 I form a 40 groove, the sides 31 and 32 of which are adapted to engage the ends of the strip 6. Elastic and compressible cushions 33, preferably formed of rubber, are mounted in the sides of the slot adjacent the edges thereof, the result being that when the plate 29 is pressed downwardly against the platen, the rubbers 33 will operate to align the entry strip 6 if it has not been placed in correct position on the pins 5. I at first tried having the rubber on only one of the edges of the slot but in practice I discovered that I could not be sure of it operating to properly align the entry strip 6 unless there was a strip of rubber on 50 each edge of the channel into which the ends of the pins 5 and 5' extend.

It will be obvious from the hereinbefore contained description that the spring 24 operates to normally hold the pin 28 at the upper end of the 55 arcuate slot 27. The means for normally holding the plate 29 pressed against the platen, so as to hold the strip 6 in position, comprises a hook 34 which is engaged by a detent 35 which is pivotally secured to the underside of the plate 29. 60 The detent 35 is normally held in the position shown in Fig. 5, a spring 36 being provided to hold it in that position. A pin 37 is fixedly secured in said detent adjacent one end. This pin 37 extends through a slot 38 formed in the plate 65 29, the upper end of the pin 37, which extends above the upper surface of the plate 29, is provided with a suitable knob 39 for convenient manual manipulation. So that by moving the pin 37, in this slot 38 the detent will be disengaged 70 from the hook 34 and the plate 29 will be automatically moved through the medium of the spring 24 to its upward position as clearly seen in Fig. 4.

In using the board there is always danger that 75 in the printing of the entry slip 6, the vertical

columns thereon will not align with the vertical columns on the master sheet and if this should occur it is possible for the numerals, entered in the space in the columns, to be out of alignment. I overcome this by defining the columns on the 5 entry strips as clearly seen in Fig. 9 from which it will be apparent, that for example the space on the entry strip in the vertical column 40 will be narrower than the space 41 in the vertical column on the master sheet. This I bring about by printing a plurality of vertical lines 42, 43 and 44. The result of this is that any irregularity in the printing is automatically overcome and correct registration is ensured. In using the board, the operator first places the entry strip 6 on the 10 pins 5 and 5' and presses the plate 29 down so that the rubber strips 33 will align the entry strip 6 and hold it securely in place. This operation causes the plate 29 to contact the pin 28 and move it to the bottom of the arcuate slot 27 moving the disk counter clockwise against the action of the spring 24 thus moving the pawl 22 over the teeth of the ratchet 20 to a position where it will engage one of said teeth.

As described in my copending application, if 25 the operator released the plate at this point, the spring would automatically move it upwardly and through the medium of the gears and ratchet rotate the worm 12 and shift the position of the spacer. It has been found, however, that it is 30 sometimes necessary for the operator to leave the board before he has completed his entry on the strip and with that arrangement the operator would have to provide some means or some one to hold the plate down. By means of my improvement the detent on the bottom of the plate will engage the hook and will hold the plate firmly 35 down against the entry strip until the operator manually shifts the position of the pin 37 in the slot 38 which will have the effect of disengaging 40 the detent from the hook 34. The board will then automatically be elevated and through the medium of the ratchet and gears the worm will 45 be rotated and the spacer automatically shifted to the next line.

Having described my invention what I regard as new and desire to secure by Letters Patent is—

1. A writing board having a platen for supporting a master sheet upon which entries are to be made, a spacer mounted adjacent said platen 50 and adapted for movement along one side of said platen, said spacer being provided with means for locking an entry strip on said master sheet, a movable element, means actuated by the movement of said element for automatically moving said spacer along said platen a predetermined distance after each entry is made on said master sheet, there being a slot in the lower surface of said movable element into which the entry strip holding means project, elastic and compressible 60 cushions located on the edges of said slot whereby the movement of said element into lowered position operates to clamp said entry strip on the master sheet.

2. A writing board comprising a platen for supporting a master sheet upon which entries are to be made, a slot in said platen along one side thereof, a worm mounted on the inside of said platen parallel to said slot, a plate riding on said worm, pins carried by said plate projecting 70 through said slot, a plate hinged on said platen and adapted to be pressed against said platen, each time an entry is to be made of the said master sheet, a slot in the lower surface of said plate into which said pins project, elastic and 75

compressible cushions located on the edges of said slot and means operated by the movement of said hinged plate for rotating the worm and thereby imparting motion to the plate riding on said worm.

3. A writing board comprising a platen for supporting a master sheet upon which entries are to be made, a slot in said platen along one side thereof, a worm mounted on the underside 10 of said platen parallel to said slot, a plate riding on said worm, pins carried by said plate and projecting through said slot, a plate hinged on said platen and adapted to be pressed against said platen each time an entry is to be made on said 15 master sheet, means operated by the movement

of said hinged plate for rotating the worm and thereby imparting motion to the plate riding on said worm, said mechanism consisting of a ratchet and pawl and cooperating gears, a gear casing secured to the platen adjacent the upper 5 end of the worm, there being an arcuate slot in the inner face of said gear casing, a disk secured to the larger gear, a pin in said disk which extends through said arcuate slot mounting the periphery of said disk, a circular recess in one side 10 of said disk, a coil spring mounted therein, one end of which is secured to the disk and the other to the gear casing whereby the pin in said arcuate slot is normally held in the upper end thereof.

EDWARD J. GERETY. 15
